[57] **CLAIM**

The ornamental design for an illuminated telephone handset support attachment, substantially as shown and described.

DESCRIPTION

FIG. 1 is a side elevational view of an illuminated telephone handset support attachment showing my new design, a conventional cradle-type telephone instrument being fragmentarily shown in assembled relation therewith in dotted outline, and a dry cell battery, a short length of electrical cable and a memo notebook being also shown in dotted outline;

FIG. 2 is a rear view thereof, a pen partially received in the pen holder of the attachment being shown in dotted outline;

FIG. 3 is a front view thereof;

FIG. 4 is a top view thereof; and

FIG. 5 is a bottom view thereof.

The attachment is laterally symmetrical about a central vertical plane. The broken lines are shown for illustrative purposes only.
